[57] CLAIM

The ornamental design for the sports cap brassiere, as shown and described.

DESCRIPTION

FIG. 1 is a front elevational view of a sports cap brassiere showing my new design;

FIG. 2 is a rear elevational view thereof;

FIG. 3 is a top plan view thereof;

FIG. 4 is a bottom plan view thereof;

FIG. 5 is a side elevational view thereof, it being understood that the right and left sides are mirror images of one another;

FIG. 6 is a front elevational view thereof;

FIG. 7 is a rear elevational view of a second embodiment of a sports cap brassiere showing my new design;

FIG. 8 is a top plan view thereof;

FIG. 9 is a bottom plan view thereof;

FIG. 10 is a right side elevational view thereof, it being understood that a left side view is a mirror image thereof;

FIG. 11 is a front elevational view of a third embodiment of a sports cap brassiere showing my new design;

FIG. 12 is a front elevational view of a fourth embodiment of a sports cap brassiere showing my new design; and,

FIG. 13 is a fragmentary view of a fifth embodiment of a sports cap brassiere showing my new design.

The top, bottom, and side views of FIGS. 11, 12, and 13 are essentially the same as FIG. 1.
